UNITED STATES PATENT OFFICE.

DAVID M. PARKER, OF BOSTON, MASSACHUSETTS.

GAS-COCK.

SPECIFICATION forming part of Letters Patent No. 314,874, dated March 31, 1885.

Application filed April 14, 1884. (No model.)

To all whom it may concern:

Be it known that I, DAVID M. PARKER, of Boston, in the county of Suffolk and State of Massachusetts, have invented certain new and 5 useful Improvements in Gas-Fixtures, of which the following is a specification.

The object of my invention is to provide a simple, cheap, convenient, efficient, and durable check for reducing the pressure and 10 regulating the flow of gas through the burner, so as to prevent undue pressure at the point of combustion; and it consists in the construction, combination, and arrangement of a self-clearing check with the stop-cock of the 15 fixture, so that the act of opening and closing the same shall remove all sediment or coal-tar from the check-passage which may be deposited while the gas is burning.

Figure 1 represents a side elevation of a 20 gas-fixture having my invention applied thereto. Fig. 2 represents a horizontal longitudinal section of a gas-fixture constructed according to my invention. Fig. 3 represents a side elevation of the stop-cock removed from the 25 fixture, showing the gas-passage. Fig. 4 represents a similar view.

A represents a small gas-fixture provided with a burner, B, as heretofore in general use, having a stop-cock, E, of peculiar construction, being fitted within the tapering opening F gas-tight, as heretofore. Now, in order to check the flow of gas through the stop-cock E when turned to the proper position to open the gas-passage, I construct the tapering body or stop with an orifice or cavity, L, 35 of suitable depth and size to allow the gas to pass freely through the same to the small check-groove P, and thence through the right-angle passage or opening R, extending toward the center of the plug or stop and uniting with the outlet-hole T, which communicates with the interior opening or tube supplying the burner B.

This check-groove P, being formed smaller 45 than any other portion of the gas-passage, regulates the flow of gas through the same and counteracts the excessive pressure by checking the flow at this point, so that only

the desired amount can reach the tip of the burner to sustain perfect combustion when 50 lighted and insure a clear, soft, steady light. The said check-groove P, being smaller than any other portion of the passage, the flow of gas through the same will cause the impurities contained in the gas to be deposited in 55 this groove, and if there were no means of removal would soon fill up the same to such an extent as to prevent a suitable quantity of gas passing to properly supply the burner, which objection I obviate by constructing a 60 screw, N, or other inwardly-projecting device that will fit within the said groove P as it is turned past the projecting end of the screw N, which scrapes or removes the same therefrom into the openings or cavities L and 65 T, located each side of or at each end of the said groove P, and which are of such larger capacity as to receive and retain the impurities deposited without interfering with the free passage of the gas through the said cavities or openings to the burner B, as before 70 described. It will be seen that the screw N is inserted into a suitably-formed hole made in the fixture to receive it, as shown in the drawings, and that the inward-projecting end 75 of said screw E enters the said groove P when the said stop-cock is partially opened or partially closed, and when the stop-cock is fully opened the point of the screw is within the opening or cavity R, and when the stop-cock 80 is fully closed the point of the screw is within the cavity L.

Having thus described my invention, what I claim is—

A gas-fixture having a stop-cock, E, provided with a check-groove, P, and openings or cavities L and T, forming the gas-passage through the cock, and a screw, N, adapted to pass through said groove when the stop-cock 85 is turned, substantially as described, as and 90 for the purposes set forth.

DAVID M. PARKER.
